SLUSH PUMP

Albert A. Ashton, Houston, Tex., assignor to
 Emsco Derrick & Equipment Company, Los
 Angeles, Calif., a corporation of California

Application January 13, 1943, Serial No. 472,224

7 Claims. (Cl. 308—3)

My invention relates to an improvement in slush pumps of the type employed in the drilling of wells by rotary method, and relates in particular to a simple, yet effective, mud pump construction.

It is an object of the present invention to provide a pump of light weight and simple construction having as a part thereof a removable cross head so formed that it may be manufactured at minimum cost and is rigid and self-sustaining when secured in operative position. Through the simplicity of construction achieved therein, this slush pump structure achieves light weight without sacrifice of strength or any other desirable quality.

It is an object of the invention to provide a slush pump having a replaceable unitary cross head guide and means of simple and durable character whereby the cross head guide is secured in operative position between the fluid and power ends of the pumping device.

It is a further object of the invention to provide a cross head guide member, as a separate unit for use in a power operative device of this general character, this cross head guide member having a base portion whereby it may be secured to a supporting wall in the device, and having as a part thereof sealing means for cooperation with the piston rod of the device.

It is an object of the invention to provide a pump structure, or a device of similar character, having a removable and replaceable cross head guide for attachment means at one end thereof, and with the other end thereof essentially open, the frame work of the pump structure having means for cooperative engagement with the attachment means at one end of the cross head guide to establish alignment of the cross head guide and piston rod as the cross head guide is moved into its operative position in the structure.

Further objects and advantages of the invention will be brought out in the following part of the specification.

Referring to the drawing, which is for illustrative purposes only,

Fig. 1 is a side view of a slush pump incorporating my invention, a portion of the device being cut away to show the removable cross head guide.

Fig. 2 is an enlarged cross section taken on a plane represented by the line 2—2 of Fig. 1.

Fig. 3 is a perspective view of the cross head guide member shown in Fig. 1.

Fig. 4 is a perspective view showing an alternative form of the cross head guide member with forked connecting rod.

The slush pump 10 shown in Fig. 1 has a pump unit 11 of double acting type and a power unit 12 comprising a rotary member 13 such as a gear arranged to be driven through a pinion 14. The gear 13 carries a crank member 15 arranged to reciprocate a connecting rod 16.

The cylinder 17 of the unit 11 has therein a piston 18 adapted to be reciprocated by a piston rod 19. The pump unit 11 and the power unit 12 are mounted on a rigid base structure 20, and within the housing 21 of the power unit 12 there is a supporting member 22, referred to herein-after as the supporting wall for a unitary cross head guide 23.

Referring to Fig. 3, this unitary cross head guide 23 is essentially a cylinder having side portions cut away to produce windows or openings 24 and leave upper and lower guide bars 25 which are arcuate in cross section and extend in parallel relation from a circular base 26, this member 26 being sometimes referred to herein as the head of the cross head guide member, since it provides a transverse wall substantially closing the leftward end of the cross head guide member, except for the provision of an opening 27, through which a portion of the piston rod passes. This base or head 26 also carries as a unitary part of the cross head member packing means or oil stripping means 28, Fig. 1, for engagement with the surface of the piston rod to prevent oil from being carried out of the gear and cross head chamber 29, and likewise to prevent rightward movement of the piston rod 19 from carrying foreign material into the cross head member 23 and into the chamber 29.

The head or base 26 of the unitary cross head guide member 23 has shoulder means for cooperative engagement with the supporting wall 22 to position the member 23 in its proper relation to the piston rod 19 and the cross head 30 which is connected to the rightward end of the piston rod 19. This shoulder means comprises a radial face or shoulder 31 and an annular face or shoulder 32 carried by a flat circular extension 33 which projects leftward from the transverse plane defined by the radial face 31. From the circular wall portion 33 there leftwardly extends a short cylindric wall 34 defining a packing chamber 35 which forms a part of the sealing or stripping means 28, shown in Fig. 1.

The supporting wall 22 has shoulder means to cooperate with the shoulders 31 and 32 of the guide member 23, such shoulder means comprising the rightward plane face 55 of the wall 22, this plane 55 being perpendicular to the axis of

the piston rod 19, and an annular face 36 which defines an opening in the supporting wall 22. When the guide member 23 is secured in place by screw means, such as stud bolts 31, the head 26 of the guide member 23 lies in transverse relation to the opening defined by the shoulder 36, and the annular shoulder 32 of the member 23 cooperates with the shoulder 36 to establish coaxial alignment of the guide member 23 and the piston rod 19.

In the form of the invention shown in Fig. 3, the forward ends 38 of the cross head guide bars 25 are tied together by arched wall segments 39. The connecting rod 16 extends into the open end of the guide member 23 and has thereon an eye 40 which is received in a cavity 41 in the cross head 30, and carries therein a roller bearing 42 for engagement with a bearing pin 43, the ends of which are seated in the side walls 44 of the cross head 30, as shown in Fig. 2.

A feature of my present invention is that the unitary cross head guide member 23 may be readily machined from a single piece of metal, for example, a casting, by use of simple turning and grinding operation. After it is completed and during its installation and use in the device shown in Fig. 1, no adjustment of the guide bars 25 is required, since these guide bars 25 are rigidly supported and machined in fixed relation and are thereafter maintained in this fixed relation. Replacement of the unitary guide member 23 when it has become worn is more economical than the replacement of adjustably secured parts such as employed in ordinary cross head guides, and those difficulties arising from attempted adjustments by unskilled workers are avoided. The removal and replacement of the unitary cross head guide member 23, due to the simplicity of the supporting and securing means employed therefor, does not require the services of a machinist especially skilled in the adjustment of bearing parts. A further feature of the invention is that the guide member 23 is supported in such relation to the crank member 15 that at the end of each rightward reciprocation, a small portion of the cross head 30, as indicated by dotted lines 30' of Fig. 1, will project from the rightward end of the guide member 23 to expose a portion of the upper bearing face of the cross head 30 to the path of oil produced in the chamber 29 by the action of the rotating and moving parts which operate therein.

In Fig. 4 I show a cross head guide member 23' which embodies the general features hereinbefore discussed with relation to the guide member 23. It has upper and lower guide bars 25' of arcuate cross section, disposed with relation to the axis of the guide member 23 so as to define an imaginary cylinder. The forward ends 38' of the guide bars 25' are disclosed without means to tie them together, such as the members 39 shown in Fig. 3. These guide bars 25' are reinforced by ribs 46, which project from a circular base 26' analogous to the base 26 of Fig. 3. In this form of the invention, the piston rod 19' may be reciprocated through use of a cross head 30' having flattened sides from which the ends of a pin 43' project into engagement with the ends of the forks 47 of a bifurcated connecting rod 16'. The gap 48 between the forks 47 of the connecting rod 16' has a lateral dimension greater than the width of the guide bars 25'.

I claim as my invention:

1. In a pumping device of the character described, the combination of: a reciprocating

5 pump unit having a piston rod extending therefrom; a supporting wall in transverse relation to the axis of said piston rod and having an opening therein, through which a portion of said piston rod extends; a crank member supported in operative position on the opposite side of said wall from said pump unit; a unitary cross head guide member having at one end thereof a head through which said piston rod passes and having its other 10 end open, said head having a shoulder to cooperate with said opening in said supporting member for aligning said guide member with said piston rod and there being upper and lower rigid guide bars extending from said head in parallel relation to the axis of said piston rod, said guide member being removably secured to said supporting wall in a position with its open end projecting toward said crank member and with its head in transverse relation to said opening of said 15 supporting wall; a cross head slideable in said guide member and being connected to said piston rod for reciprocation thereof, and having upper and lower bearing faces to engage said side bars; and a connecting rod connecting said crank member to said cross head.

2. In a pumping device of the character described, the combination of: a reciprocating pump unit having a piston rod extending therefrom; a supporting wall in transverse relation 30 to the axis of said piston rod and having an opening therein, through which a portion of said piston rod extends; a crank member supported in operative position on the opposite side of said wall from said pump unit; a unitary cross head guide member having at one end thereof a head through which said piston rod passes and having its other end open, the head of said guide member being removably secured to said supporting wall and having its open end projecting toward 35 said crank member and with its head in transverse relation to said opening of said supporting wall; a cross head slideable in said guide member and being connected to said piston rod for reciprocation thereof; and a connecting rod connecting 40 said crank member to said cross head.

3. In a pumping device of the character described, the combination of: a reciprocating pump unit having a piston rod extending therefrom; a supporting wall in transverse relation 45 to the axis of said piston rod and having coaxially with said piston rod a circular opening therein, through which a portion of said piston rod extends; a crank member supported in operative position on the opposite side of said wall from said pump unit; a unitary cross head guide member having a circular base at one end thereof, said guide member being characterized by being of essentially tubular form and having side portions thereof cut away so as to leave guide bars 50 extending in parallel relation from said base thereof, said base having an annular shoulder to extend into said circular opening of said supporting wall for producing alignment of said guide member with said piston rod, said guide member being removably secured to said supporting wall in a position projecting from said wall toward 55 said crank means; a cross head slideable in said guide member and being connected to said piston rod for reciprocation thereof and having upper and lower bearing faces to engage said side bars; and a connecting rod connecting 60 said crank member to said cross head.

4. In a pumping device of the character described, the combination of: a reciprocating

pump unit having a piston rod extending therefrom; a supporting wall in transverse relation to the axis of said piston rod and having coaxially with said piston rod a circular opening therein, through which a portion of said piston rod extends; a crank member supported in operative position on the opposite side of said wall from said pump unit; a unitary cross head guide member having a circular base at one end thereof, said guide member being characterized by being of essentially tubular form and having side portions thereof cut away so as to leave guide bars extending in parallel relation from said base thereof, said base having an annular shoulder to extend into said circular opening of said supporting wall for producing alignment of said guide member with said piston rod, said guide member being removably secured to said supporting wall in a position projecting from said wall toward said crank means, said guide member also comprising sealing means carried by said base in position to engage said piston rod; a cross head slideable in said guide member and being connected to said piston rod for reciprocation thereof and having upper and lower bearing faces to engage said side bars; and a connecting rod connecting said crank member to said cross head.

5. In an article of manufacture comprising a unitary cross head guide member for use in a pumping device having a piston rod and a cross head reciprocated by crank means and a casing: a removable open ended base having guide bars extending therefrom in parallel relation and free

of said casing, a supporting means in transverse relation to the axis of said piston rod; and means on said base for cooperation with said supporting means to hold the same in operative alignment with said piston rod.

6. In an article of manufacture comprising a unitary cross head guide member for use in a pumping device having a piston rod and a cross head reciprocated by crank means and a casing: 10 a base having guide bars extending therefrom in parallel relation and free of said casing, said guide bars being arcuate in cross section and being positioned so as to define an imaginary cylinder, the ends of said guide bars opposite said base 15 defining an open end for said cross head guide; a support with which said base is removably associated; and sealing means carried by said base for cooperating with said piston rod.

7. In a device of the character described, in 20 combination with a reciprocating pump unit including the piston rod, crank member, and cross-head: a circular plate having a diametrically smaller annular projection and a chamber extended from said projection for a packing unit, 25 said plate provided with a substantially tubular open-ended guide; a support for said plate in transverse relation to the axis of said piston rod, said support having an opening to receive the annular projection thereof; and the plate and support 30 port provided with mutually engaging means removably to hold the plate and guide in position.

ALBERT A. ASHTON.
